UNITED STATES PATENT OFFICE.

FREDRICK MARTINEK AND OTTO ALBERT LUSK, OF CHICAGO, ILLINOIS.

DESIGN FOR A NIPPLE FOR BICYCLE-VALVES.

SPECIFICATION forming part of Design No. 28,701, dated May 24, 1898.

Application filed April 11, 1898. Serial No. 677,236. Term of patent 3½ years.

To all whom it may concern:

Be it known that we, FREDRICK MARTINEK and OTTO ALBERT LUSK, citizens of the United States, residing in the city of Chicago, county 5 of Cook, and State of Illinois, have invented and produced a new and original Design or Shape for a Nipple for Bicycle - Valves, of which the following is a specification, reference being had to the accompanying drawings, forming part thereof.

Figure 1 is a side elevation of our new design. Fig. 2 is an end view of the same.

As shown in the drawings, the features of our design are a vertical cylindrical form *a*, 15 at the upper end of which are joined two horizontal cylindrical branches *b b*, which extend at right angles to the vertical part, thus mak-

ing a T-shaped configuration, as shown. The outer ends of the branches *b b* are closed by circular pieces *c c*, having milled edges *d d*, 20 as shown in Fig. 2.

Having thus described our invention, what we claim as new, and desire to secure by Letters Patent, is—

The design for a nipple for bicycle-valves, 25 substantially as herein shown and described.

In testimony whereof we affix our signatures in presence of two witnesses.

FREDRICK MARTINEK.
OTTO ALBERT LUSK.
